UNITED STATES PATENT OFFICE.

CLINTON C. DE WITT, OF ST. LOUIS, MISSOURI, ASSIGNOR OF ONE-THIRD
TO JOHN C. SHANK, OF SAME PLACE.

COMBINED GANG-PLANK AND CONVEYER.

SPECIFICATION forming part of Letters Patent No. 558,361, dated April 14, 1896.

Application filed October 21, 1895. Serial No. 566,359. (No model.)

To all whom it may concern:

Be it known that I, CLINTON C. DE WITT, of the city of St. Louis, State of Missouri, have invented certain new and useful Improvements in a Combined Gang-Plank and Conveyer, of which the following is a full, clear, and exact description, reference being had to the accompanying drawings, forming a part hereof.

10 My invention relates to a combined gang-plank and conveyer; and it consists in the novel construction, combination, and arrangement of parts hereinafter described and claimed.

15 In the drawings, Figure 1 is a side elevation of my combined gang-plank and conveyer, the same being applied for practical use. Fig. 2 is a top plan view of the gang-plank, parts thereof being broken away to 20 more clearly illustrate the same. Fig. 3 is an enlarged vertical sectional view taken approximately on the indicated line 3 3 of Fig. 1. Fig. 4 is an enlarged sectional view taken approximately on the indicated line 4 4 of 25 Fig. 3. Fig. 5 is a cross-sectional view taken approximately on the indicated line 5 5 of Fig. 4. Fig. 6 is an enlarged sectional view taken approximately on the indicated line 6 6 of Fig. 3. Fig. 7 is a view in perspective of 30 an inclined walk made use of in carrying out my invention.

Referring by numerals to the accompanying drawings, 1 indicates the deck of a vessel, from which deck rises at the proper position 35 a mast 2, in the top end of which is arranged for rotation a grooved-wheel or pulley 3. A boom 4 is arranged to operate upon said mast in the usual manner, said boom being provided on its outer end with a grooved wheel 40 or pulley 5.

Bolted to the deck 1 at a point adjacent the mast 2 and the rail of the vessel is a bed-plate 6, the same being provided with a center bearing 7 and with concentric segmental 45 tracks 8 on its top surface. Formed in said bed-plate are slots 9, the purpose of which will be presently shown.

10 indicates a plate, the same being provided with a center bearing 11, that rests directly upon the center bearing 7, there being a bolt 12 passed through said bearings 11 and

7. Depending from the under side of the plate 10 are parallel bearings 13, in which are journaled for rotation wheels 14, the same bearing directly upon the tracks 8. Arranged 55 upon opposite sides of the plate 10 are engines 15 of any suitable design, there being a single crank-shaft 16 for said engines. Fixed upon said crank-shaft adjacent each one of said engines is a gear-wheel 17.

Extending upwardly from the plate 10 on opposite sides thereof are frames 18, the upper ends of which are formed into journal-boxes 19, and in said boxes is mounted for rotation a shaft 20. Suitable journal-boxes 65 21 are arranged upon said shaft 20 and extend upwardly and are bolted to timbers 22, the same extending parallel with each other over and above the rail of the vessel. Located upon the top surfaces and outer edges 70 of said timbers 22 are smaller timbers 23, and extending outwardly from said timbers 23 are supporting-beams 24, that are supported by braces 25, and located upon said beams 24 and extending parallel with the timbers 22 75 are planks 26, the same being arranged to form walks. Extending upwardly from the side of these planks 26 are supporting-rods 27, the upper ends of which are provided with rings 28, through which are passed rails or 80 ropes 29.

Fixed to the inner faces of the timbers 22 and connecting the same are timbers 30, the same being somewhat shorter than are said timbers 22.

85 Located upon the outer ends of the shaft 20 are drums 31, on which may be wound ropes or cables, as desired, and fixed upon said shaft adjacent each of the frames 18 are gear-wheels 32, the same meshing with the gear-wheels 17 90 previously mentioned.

95 Fixed upon the shaft 20 inside the frames 18 are sprocket-wheels 33. Loosely mounted upon the shaft 20, just inside each of the boxes 21, is a sprocket-wheel 34, the tops of which extend into a plane just above the tops of the timbers 22, and the inner faces of the hubs of said sprocket-wheels 34 are formed into clutch-faces 35. Formed upon the center of the shaft 20, between these two sprocket-wheels 34, is a feather 36, and arranged to slide upon the thus-feathered portion of said

shaft 20 are collars 37, the outer portions of which are formed into clutch-faces 38, that are arranged to oppose the clutch-faces 35. Formed in these collars 37 are peripheral 5 grooves 39, in which grooves are arranged collars 40, the same being provided with downwardly-pending portions 41, that carry anti-friction-rollers 42.

Extending transversely between the frames 18 is a bar 43, from the center of which extends upwardly a pin 44, the same having a disk 45 pivoted upon its upper end, in which disk are formed oppositely-arranged segmental slots 46, in which slots the antifriction-rollers 42 operate. Formed integral with and extending outwardly from the disk 45 is an operating-handle 47.

Journaled in suitable bearings 48, fixed to the under side and outer ends of the planks 26, is a shaft 49, the same carrying a pair of frames 50, the lower ends of which are formed into feet. Fixed upon said shaft 49 adjacent said frames 50 are sprocket-wheels 51, and sprocket-chains 52 pass over the sprocket-wheels 51 and the sprocket-wheels 33 previously mentioned. Fixed upon said shaft 49, just inside the timbers 22, are sprocket-wheels 53, and sprocket-chains 54 pass around and connect said sprocket-wheels 53 with the sprocket-wheels 34 previously mentioned. Passing transversely between said sprocket-chains 54 and fixed in the lengths thereof at equal distances apart are rods 55, which carry blocks 56, the upper ends of the upper ones 35 of which travel in a plane above the plane occupied by the tops of the planks 26.

57 indicates an inclined timber provided with cleats 58, and extending laterally from the upper end of said inclined timber are 40 metallic bars 59, the ends of which are formed into hooks 60, that are engaged around the shaft 16 when said timber 57 is in proper position. A chain or cable, such as 61, passes over the grooved wheels 3 and 5 and engages 45 a chain 62, the lower ends of which are secured to hooks 63, fastened to the sides of the planks 26. Flexible connections, such as 64, (shown by dotted lines in Fig. 3,) extend upwardly through the slots 9 to the steam-chests of the 50 engines 15.

Assuming that the gang-plank is in an elevated position and the boat is landing and it is desired to lower said gang-plank into the position where the passengers and freight can be landed, the windlass or drum on which the chain 62 is wound is rotated so that said chain 62 will unwind, and by so doing the entire gang-plank will lower, as indicated by dotted lines in Fig. 1, to an approximately 55 horizontal position, or until the feet of the frames 50 will be located upon the landing. The passengers from and to the vessel may now pass over the gang-plank, those landing 60 from said vessel passing upon one side of said gang-plank and those entering said vessel passing along the opposite side of said gang-plank. If it is desired to transfer a number

of packages or bales of freight from the vessel to the landing, the attendants place the inclined timber 57 in proper position and roll 70 or pass the packages or bundles of freight up said timber and onto the sprocket-chains 33. The engines 15 are now started, so that said chains 33, carrying the blocks 56, move in the direction as indicated by the arrow A, Fig. 2, 75 and as fast as the bundles or packages are located upon said chain they will be moved by said chain and blocks to the outer end of the gang-plank and upon the landing. Rotary motion from the crank-shaft 16 is imparted 80 to the shaft 20 by reason of the gear-wheels 17 meshing with the gear-wheels 32, and the rotary motion of said shaft 20 is imparted to the sprocket-wheels 34 as soon as the disk 45 has been moved in the direction indicated by 85 the arrow B, Fig. 4, which necessarily throws the collars 37, carrying the clutch-faces, into the clutch-faces on the hubs 35 of said sprocket-wheels 34. The motion of the sprocket-chains 54 may be reversed if desired, 90 and by so doing the freight from the landing can be conveyed onto the boat. After the passengers and freight have been transferred to and from the boat the windlass or drum on which the chain 61 is wound is rotated and 95 the gang-plank is raised into an elevated and out-of-the-way position. When the clutch-faces 38 are thrown out of engagement with the clutch-faces 35, the engines may be operated and the shaft 20 rotated to wind the 100 cables or chains upon the drums 31 and not operate the sprocket-chains 54. By thus providing the drums 31 on the end of the shaft 20 I do away with the capstan ordinarily used on vessels and the engine for operating the 105 same.

The sprocket-chains 52 are for the purpose of relieving the sprocket-chains 54 of the strain required to rotate the shaft 49. The entire gang-plank can be swung laterally as 110 desired, this being possible by simply pivoting the plate 10, mounting the same on the wheels 14, and when said gang-plank is so swung the flexible connections 64 to the engines will readily pass through the curved 115 slots or apertures 9 in the bed-plate 6.

A combined gang-plank and conveyer of my construction possesses superior advantages in point of simplicity, durability and general efficiency, can be operated very economically in point of power, greatly facilitates the handling of bundles of freight to and from a vessel, freight and passengers can be taken on the vessel simultaneously, a capstan and engine for operating the same done away with by locating the drums on the ends of the main shaft of said gang-plank, and much time and labor are saved by the use of said conveyer and gang-plank.

I claim—

1. In a combined gang-plank and conveyer, a bed-plate located upon the deck of a vessel, a plate arranged to rotate upon said bed-plate, bearings arranged upon said rotating

plate, a shaft mounted for rotation in said bearings, a gang-plank constructed in two sections extending laterally from said shaft, an endless carrier operating between said 5 mating portions and driven from said shaft, drums arranged upon the ends of said shaft, and suitable means arranged upon the rotating plate for driving said shaft.

2. In a combined gang-plank and conveyer, 10 a bed-plate, a plate arranged to rotate upon said bed-plate, bearings arranged upon said rotating plate, a shaft mounted for rotation in said bearings, drums located upon the ends of said shaft, means carried by the rotating 15 plate for operating said shaft, a gang-plank constructed in two parallel sections swung

upon said shaft, a pair of sprocket-wheels loosely mounted upon the shaft at one end of said gang-plank, a shaft arranged for rotation at the outer end of the gang-plank, sprocket-wheels mounted thereon, sprocket-chains passing around said sprocket-wheels, bars arranged transversely between said sprocket-chains to form an endless carrier, and suitable means for causing the first-mentioned 20 sprocket-wheels to rotate with the main shaft.

In testimony whereof I affix my signature in presence of two witnesses.

CLINTON C. DE WITT.
